SPEED CONTROL FOR SQUEEZE ROLLS

Charles E. Olive, Drummondville, Quebec, Canada, assignor to Celanese Corporation of America, a corporation of Delaware

Application April 12, 1940, Serial No. 329,267

10 Claims. (Cl. 100—47)

This invention relates to squeeze rolls for extracting liquid from wet masses of material, and relates more particularly to an automatic speed control for the squeeze rolls.

An object of this invention is the provision of simple, efficient and inexpensive means for extracting liquid from a wet mass of material.

Another object of this invention is to provide an improved arrangement for controlling the speed of squeeze rolls. A further object of this invention is to provide a squeeze roll arrangement wherein the speed of the squeeze rolls is automatically controlled by the feed of the mass to be extracted.

Other objects of this invention, together with certain details of construction and combinations of parts, will be apparent from the following detailed description and claims.

In the accompanying drawings wherein one embodiment of the invention is shown;

Figure 1 is a side elevational view, more or less diagrammatic, showing the relation of the material control curtain in the feeder chute for feeding the wet mass of material to the squeeze rolls,

Figure 2 is a plan view, partly in section and on a slightly enlarged scale, of the lever system for controlling the micro-switches,

Figure 3 is a view taken on line 3—3 in Figure 2,

Figure 4 is a front elevational view, partly in section, of the jogging timing device,

Figure 5 is a view taken on line 5—5 in Figure 4, and

Figure 6 is a wiring diagram for the control of the motor for driving the squeeze rolls.

Like reference numerals indicate like parts throughout the several views of the drawings.

Referring now to the drawings, the reference numeral 7 indicates generally the usual three roll squeeze roll arrangement for extracting liquid from wet masses passed therethrough. As is well known, such squeeze rolls operate at optimum efficiency when the rolls are kept full of the material being extracted. In accordance with this invention, there is provided means for automatically controlling the speed of the squeeze rolls for maintaining said squeeze rolls full of material while they are rotating and to stop the rotation thereof, or shut them down, when insufficient material is fed thereto to keep them full. To this end, a feeder chute has swingably mounted between its side walls 9 and 9' a control curtain which may be of metal or any other suitable material. The free end of the control curtain is curved in the direction of the feed of the

material. The position of curtain 11 as determined by the depth or thickness of the mat of material in the chute, controls the rotation of the squeeze rolls by means which will hereinafter be described.

The control curtain 11 is carried by a pair of triangular web arms 12 and 13. The apex of arm 12 is attached to and is adapted to rock stub shaft 14 in casing 15 suitably fixed to side wall 9' of the chute, the shaft 14 being held in position by means of a collar 16 and set screws 17. The apex of arm 13 is fixed to a shaft 18 on which is carried a counterbalance arm 19 and a counterbalance weight 21 adjustable along said arm 19, the counterbalance weight being adapted to be held in adjusted position by a set screw 22. The counterbalancing means, i. e. arm 19 and weight 21, are adjusted to allow the curtain 11 to reach its lowermost or A position as shown in Figure 1 of the drawings.

Movement of the control curtain 11 rotates shaft 14 and thereby cams 23, 24 and 25 integral with collars 26, 27 and 28, respectively, which are suitably attached to the shaft 14. The cams are so arranged as to give three control positions, indicated by reference characters A, B and C in Figure 1, to control curtain 11. These control positions may be changed where necessary by resetting cams 23, 24 and 25. The normal, or desired, depth of the material in the chute is between positions B and C with the control curtain 11 riding on top of the mat of material. If the material comes into the chute faster than the squeeze rolls pass it on, the depth of the mat of the material will increase and the curtain will therefore rise above the position C thus rotating shaft 14. This rotation of the shaft causes cam 23 to rock a lever 29, which is bifurcated at one end and carries a rotatable cam follower 30 in the bifurcation, about a pivot 31 thus depressing a plunger 32 of a micro-switch arranged in switch box 33. The micro-switch is adapted to close a circuit to a pilot motor 34 which will actuate a controller arrangement, generally indicated by reference numeral 34', to increase the speed of a motor 35 which drives the squeeze roll 7.

When the feed of the material to chute 8 slows up and the mat of the material is of such a depth that it is below position B the drop of control curtain 11 causes cam 24 to actuate lever 36 which is substantially similar to lever 29. The actuation of lever 36 depresses plunger 37 of micro-switch 37' effecting a decrease in the speed of the squeeze rolls. Should the feed of the squeeze rolls slow up to such an extent that the

material is at all below position A, the drop of the control curtain 11 causes cam 25 to operate a lever 38, similar to levers 29 and 36, which depresses plunger 39 of micro-switch 40 and effects the shutting down of the squeeze rolls. This shutting down of the squeeze rolls permits the mat of material in the chute to build up and raise the control curtain enough to start the squeeze rolls again.

In order to effect the change in the speed of the squeeze rolls from low speed to high speed, and vice versa, without unnecessarily large changes and without hunting, there is provided a jogging timing, or switching, device, shown in Figures 4, 5 and 6, adapted to make contact intermittently in electric circuits. This device, comprises a Telechron clock motor, generally indicated by reference numeral 41, carried by a bracket 42, which rotates a shaft 43 at a speed of 1 revolution, more or less, per minute, one end of the shaft 43 being fixed to a stub shaft 44 of the motor and the other end being reduced, as at 45, and journaled in bearing bracket 46. Brackets 42 and 46 are fastened by means of screws 47 to the side of switch box 48. A fiber sleeve 49 is mounted on shaft 43, and a disc 51 and wiper discs 52 and 53, spaced from one another by spacers 54 are mounted on said insulating sleeve for rotation with shaft 43. The disc 51 and wiper discs 52 and 53 are adapted to run in oil in container 55 suitably fastened to the switch box 48. The wiper discs 52 and 53 are so arranged that contacts in each of the circuits, completed by them with disc 51, can be maintained for some definite period during each revolution. The contacts are made by means of a contact arm 56 which is continuously in contact with disc 51 and contact arms 57 and 58, pivoted at 58', which are arranged so as to have intermittent contact with wiper discs 52 and 53 respectively. Contact arms 57 and 58 may be adjusted with respect to wiper discs 52 and 53 by adjusting means such as screw 59 carried in a suitable bracket 60 fixed to the wall of the switch box, the adjusting screw carrying a fiber insulating tip or plug 61.

The contacts of the switching device are included in the circuits between the micro-switches 32, 37 and 38 and the pilot motor 34. The purpose of the arrangement of the switching device is to prevent unnecessary hunting of the controller by preventing the pilot motor 34 from operating uninterruptedly for too long a period. The device of this invention is capable of taking care of any rate of change in the flow of the material to be extracted to the squeezing rolls regardless how rapid it is. When the control curtain 11 gives an indication that the speed of the main motor 35 must be changed, the pilot motor only actuates the controller while the wiper discs 52 and 53 complete the circuits. This means that the controller can only move through a definite distance for each rotation of the cams. If, when the wiper discs 52 and 53 make contact again on their next revolution, a further change in speed is indicated or needed, the controller will move through another definite distance. This arrangement has the effect of stabilizing the control and preventing the over-running of the pilot motor.

While the present invention is applicable to the extraction of liquid from wet materials such as bagasse, paper pulp or cellulose acetate it is particularly applicable to the extraction of water from cellulose acetate after a washing treat-

ment. In this case the washer feeds the wet cellulose acetate mass into chute 8, which chute feeds the wet mass to the squeeze rollers. Prior to the employment of the squeeze roll control arrangement outlined above the moisture in the cellulose acetate after passage through the squeeze rolls was about 45%, i. e. in every hundred pounds of cellulose acetate after the water extraction by the squeeze rolls there were 45 pounds of water. With the control arrangement of the present invention it was found that the percentage of water in the cellulose acetate after passage through the squeeze rolls was 37%. Accordingly, the use of the control arrangement for the squeeze rolls makes for more economical operation.

It is to be understood that the foregoing detailed description and drawings are given merely by way of illustration and that many variations may be made therein without departing from the spirit of my invention.

Having described my invention, what I desire to secure by Letters Patent is:

1. Apparatus for extracting liquid from wet masses of material, comprising squeeze rolls, means for feeding the wet mass to said squeeze rolls, feeler means adapted to follow the surface of the wet mass and to be actuated thereby, and means under the control of said feeler means for adjusting the rate of output of said squeeze rolls.

2. Apparatus for extracting liquid from wet masses of material, comprising squeeze rolls, means for feeding the wet mass to said squeeze rolls, feeler means adapted to follow the surface of the wet mass and to be actuated thereby, and means under the control of said feeler means for adjusting the speed of rotation of said squeeze rolls.

3. Apparatus for extracting liquid from wet masses of material, comprising squeeze rolls, means for feeding the wet mass to said squeeze rolls, feeler means adapted to follow the surface of the wet mass and to be actuated thereby, and means under the control of said feeler means for controlling the operation of said squeeze rolls.

4. Apparatus for extracting liquid from wet masses of material, comprising squeeze rolls, a chute for feeding the wet mass to said squeeze rolls, a curtain in said chute adapted to be actuated by the wet mass, a shaft attached to and movable by movement of said curtain, a plurality of cams fixed to said shaft and means, including a plurality of micro-switches operated by the rotation of said cams, for adjusting the rate of output of said squeeze rolls.

5. Apparatus for extracting liquid from wet masses of material, comprising squeeze rolls, a chute for feeding the wet mass to said squeeze rolls, a curtain in said chute adapted to be actuated by the wet mass, a shaft attached to and movable by movement of said curtain, a plurality of cams fixed to said shaft and means operated by the rotation of said cams for controlling the operation of said squeeze rolls, said means including a motor for driving said squeeze rolls, a rheostat controller for regulating the speed of said motor and a pilot motor for operating said controller.

6. Apparatus for extracting liquid from wet masses of material, comprising squeeze rolls, a chute for feeding the wet mass to said squeeze rolls, a curtain in said chute adapted to be actuated by the wet mass, a shaft attached to and movable by movement of said curtain, a plurality of cams fixed to said shaft and means operated

by the rotation of said cams for controlling the operation of said squeeze rolls, said means including a motor for driving said squeeze rolls, a rheostat controller for regulating the speed of said motor, a pilot motor for operating said controller and micro-switches for controlling the operation of said pilot motor.

7. Apparatus for extracting liquid from wet masses of material, comprising squeeze rolls, a chute for feeding the wet mass to said squeeze rolls, a curtain in said chute adapted to be actuated by the wet mass, a shaft attached to and movable by movement of said curtain, a plurality of cams fixed to said shaft and means operated by the rotation of said cams for controlling the operation of said squeeze rolls, said means including a motor for driving said squeeze rolls, a rheostat controller for regulating the speed of said motor, a pilot motor for operating said controller, micro-switches for controlling the operation of said pilot motor and means for operating said pilot motor.

8. Apparatus for extracting liquid from wet masses of material, comprising squeeze rolls, a chute for feeding the wet mass to said squeeze rolls, a curtain in said chute adapted to be actuated by the wet mass, a shaft attached to and movable by movement of said curtain, a plurality of cams fixed to said shaft and means operated by the rotation of said cams for controlling the operation of said squeeze rolls, said means including a motor for driving said squeeze rolls, a rheostat controller for regulating the speed of said motor, a pilot motor for operating said controller, micro-switches for controlling the operation of said pilot motor and means for operating said pilot motor including a plurality of wiper discs, said wiper discs operating at a constant speed.

9. Apparatus for extracting liquid from wet masses of material, comprising squeeze rolls, a chute for feeding the wet mass to said squeeze rolls, a curtain in said chute adapted to be actuated by the wet mass, a shaft attached to and movable by movement of said curtain, a plurality of cams fixed to said shaft and means operated by the rotation of said cams for controlling the operation of said squeeze rolls, said means including a motor for driving said squeeze rolls, a rheostat controller for regulating the speed of said motor, a pilot motor for operating said controller, micro-switches for controlling the operation of said pilot motor and means for operating said pilot motor, said means for operating said pilot motor including a plurality of wiper discs and a motor adapted to operate said wiper discs at a constant speed.

10. Apparatus for extracting liquid from wet masses of material, comprising squeeze rolls, a chute for feeding the wet mass to said squeeze rolls, a curtain in said chute adapted to be actuated by the wet mass, a shaft attached to and movable by movement of said curtain, a plurality of cams fixed to said shaft and means operated by the rotation of said cams for controlling the operation of said squeeze rolls, said means including a motor for driving said squeeze rolls, a rheostat controller for regulating the speed of said motor, a pilot motor for operating said controller, micro-switches for controlling the operation of said pilot motor and means for operating said pilot motor including a plurality of wiper discs and a motor adapted to operate said wiper discs at a constant speed, the construction and arrangement being such that the operation of the pilot motor is interrupted at regular intervals.
